ATTORNEYS.

UNITED STATES PATENT OFFICE.

WILLIAM S. FOSTER, OF UTICA, NEW YORK.

DESIGN FOR A BEDSTEAD.

SPECIFICATION forming part of Design No. 26,855, dated March 30, 1897.

Application filed February 8, 1897. Serial No. 622,550. Term of patent 7 years.

To all whom it may concern:

Be it known that I, WILLIAM S. FOSTER, a citizen of the United States, residing at Utica, county of Oneida, and State of New York, have invented and produced a new and original Design for a Bedstead, of which the following is a specification, reference being had to the accompanying drawings, showing the same.

Figure 1 shows a perspective view of the bedstead of my design. Fig. 2 shows a plain side view, on a larger scale, of an ornament of the design employed in the bedstead.

The feature of my design is the style of bedstead shown, consisting, essentially, of hori-

zontal cross-bars and vertical spindles, and particularly the ornament *b*, substantially as shown, at the joint between the spindles and cross-bars.

What I claim is—

The design of a bedstead substantially as herein shown and described.

In witness whereof I have hereunto set my hand, at Utica, New York, this 3d day of February, 1897, in the presence of two witnesses. 25

WILLIAM S. FOSTER.

Witnesses:

E. W. JONES,
D. H. COLEGROVE.
